CLAIM

The ornamental design for a belt grinding device, as shown and described.

DESCRIPTION

FIG. 1 is a perspective view of a belt grinding device according to my design;

FIG. 2 is a left side view of the design of FIG. 1;

FIG. 3 is a front view of the design of FIG. 1;

FIG. 4 is a rear view of the design of FIG. 1;

FIG. 5 is a plan view of the design of FIG. 1;

FIG. 6 is a right side view of the design of FIG. 1; and,

FIG. 7 is an inverted plan view of the design of FIG. 1.

FIG. 2

FIG. 3

FIG. 4

FIG. 5

FIG. 6

FIG. 7
